[57] CLAIM

The ornamental design for a bottle, substantially as shown and described.

DESCRIPTION

FIG. 1 is an elevational view of a bottle showing our new design;

FIG. 2 is a top plan view;

FIG. 3 is a side elevational view looking at the bottle of FIG. 1 from the left;

FIG. 4 is a side elevational view looking at the bottle of FIG. 1 from the right;

FIG. 5 is a perspective view of the bottle;

FIG. 6 is a perspective view of the bottle generally viewed from the same location as FIG. 5 but with the bottle rotated about 180°; and

FIG. 7 is a cross-sectional plan view taken along plane 7—7 of FIG. 1.
